UNITED STATES PATENT OFFICE.

CHARLES H. HENNINGS, OF CHICAGO, ILLINOIS, ASSIGNOR TO F. AND H. MFG. CO., OF CHICAGO, ILLINOIS, A CORPORATION OF ILLINOIS.

DESIGN FOR A BIRD-CAGE STAND.

Application filed May 13, 1927. Serial No. 21,960. Term of patent 3½ years.

To all whom it may concern:

Be it known that I, CHARLES H. HENNINGS, a citizen of the Republic of Chile, residing at Chicago, in the county of Cook and State of Illinois, have invented a new, original, and ornamental Design for Bird-Cage Stand, of which the following is a specification, reference being had to the accompanying drawing, forming part thereof. The figure is a front elevational view of the bird cage stand showing my new design.

I claim:

The ornamental design for a bird cage stand as shown.

CHARLES H. HENNINGS.
